MILL

Raymond G. Tessmer, Pittsburgh, Pa., assignor, by mesne assignments, to International Process Equipment Company, Dayton, Ohio, a corporation of Ohio

Application September 24, 1958, Serial No. 763,168

4 Claims. (Cl. 241—171)

This invention relates in general to improvements in mills and more particularly to an improved arrangement for continually venting a ball mill while the latter is in operation.

In many processes utilizing ball mills, distinct advantages arise from being able to remove vapors etc. from the interior of the mill while continually operating the mill, or to operate the mill under vacuum. With previous designs of mills, the latter operations were either not generally possible, or the apparatus to accomplish the same was not dependable and unduly complicated.

The present invention in general provides a ball mill comprising a body portion which is rotatably mounted on stationary supporting structure and includes venting mechanism extending into the interior of the mill and being supported on said stationary supporting structure so as to readily provide for the continuous venting of the mill while the latter is operating. A shield element is disposed in the mill interior and is mounted on said stationary supporting structure so as to prevent the ball charge and the product being handled by the mill from entering or interfering with the venting mechanism while at the same time providing for the free access of air and vapor to the venting structure.

Accordingly, an object of the invention is to provide a material handling mechanism of the ball mill type, including novel means for continuously venting the interior of the mill during operation of the mill.

A further object of the invention is to provide a ball mill mechanism which comprises a rotatable drum member mounted on stationary end supporting structure and which includes a vent or draw pipe extending from the exterior of the drum into the interior thereof and mounted on said stationary supporting structure so as to be non-rotatable with respect thereto and with respect to the drum, and including shielding means for protecting the vent pipe from contact with a ball charge and/or a product being handled in the mill.

A still further object of the invention is to provide a ball mill arrangement comprising a rotatable drum member having hollow integral end trunnion portions which are mounted for rotary movement on stationary bearing structure, and including a draw-off or vent pipe which extends from the exterior of the drum through at least one of the end trunnions into the interior of the drum for continuously drawing off air or vapor from the interior of the mill and/or for providing a vacuum in the mill, such vent pipe being secured to the associated stationary bearing structure so as to be non-rotatable with respect to the drum member, and including a shield member supported at the ends thereof by said stationary bearing structure in non-rotatable relation to the drum member, and coacting with the interior surface of the drum member and with the vent pipe to prevent the ball charge and/or the product being handled by the mill from contacting or interfering with the vent pipe, but providing free access of air or vapor to the vent pipe so that they can be continuously removed during operation of the mill.

2

Other features and advantages of the invention will be apparent from a consideration of the following description taken in conjunction with the accompanying drawings wherein:

5 Fig. 1 is a partially sectioned, side elevational view of a ball mill mechanism embodying the instant invention;

Fig. 2 is an end elevational view of the mechanism of Fig. 1 taken from the right hand side of the latter figure;

10 Fig. 3 is a vertical sectional view taken generally along the plane of line 3—3 of Fig. 1 looking in the direction of the arrows.

Referring again to the drawings, there is illustrated a material handling mechanism of the ball mill type comprising a supporting frame structure 10 onto which is mounted a rotatable hollow body or drum 12. Drum 12 is provided with suitable covered openings (not shown) for charging and discharging of the balls and product being handled. Member 12 includes end wall 15 portions 12a and 12b, from which project integral trunnion portions 14. Trunnion portions 14 are hollow and open into the interior of the drum member for a purpose to be hereinafter described in detail. Trunnion portions 14 are rotatably mounted on pedestal elements 20 secured to frame 10. Bearings 18 of conventional type are provided on pedestals 16 to provide anti-frictional rotational movement of the trunnion portions 14 upon rotation of drum 12. Drum 12 is driven in conventional manner by means of a motor unit 26 mounted on frame 10 in conjunction with gearing mechanism 22.

In accordance with the invention, vent or draw pipe mechanism 24 is disposed in the interior of the drum member 12 and extends generally lengthwise thereof to the exterior of the drum. Vent pipe 24 is apertured for receiving vapor and/or air from the interior of the drum and carrying it to the exterior thereof and includes a dust filter member 24a for cleaning such vapor or air during its passage into and through vent mechanism 24.

35 In the embodiment illustrated, the lengthwise or horizontally extending internal portion 25 of vent pipe 24 does not extend the full length of drum 12 but is terminated as at 25a before reaching the vicinity of end wall 12b of the drum. The other or outer end of portion 25 of vent 24 is bent downwardly adjacent end wall 12a to form a generally vertically extending duct portion 26 which, at its lower end, is connected to horizontally extending outer duct portion 28. It will be seen, therefore, that vent mechanism 24 has a stepped or Z-shaped configuration in side elevation. Pipe or duct portion 28 has a fitting 28a mounted thereon for attachment to a pump or other mechanism for drawing off the air and/or vapor in the drum member 12 through the passageway formed by duct portions 25, 26 and 28.

Vent duct mechanism 24 is maintained in a predetermined stationary position by bracket structure 30 suitably secured to frame 10. Duct portion 28 is supported in anti-frictional relation on the interior surface of the associated of the trunnion members 14 by means of conventional bearings 32 which are diagrammatically illustrated. Suitable sealing or packing material may be utilized in a conventional manner in conjunction with bearings 32 and end cap member 34 for preventing the leakage of vapor through the hollow interior of trunnions 14 from the interior of the drum member. A generally axial extending secondary pipe or duct 36 may also be providing extending through duct section 28 of the vent pipe 24 and communicating with the interior of the drum member 12. Duct 36 may be for the purpose of receiving instrumentation or for supplying air or some other media into the interior of the rotary drum member 12 of the mill.

60 Within the rotatable shell or drum member 12, is dis-

55 suitable sealing or packing material may be utilized in a conventional manner in conjunction with bearings 32 and end cap member 34 for preventing the leakage of vapor through the hollow interior of trunnions 14 from the interior of the drum member. A generally axial extending secondary pipe or duct 36 may also be providing extending through duct section 28 of the vent pipe 24 and communicating with the interior of the drum member 12. Duct 36 may be for the purpose of receiving instrumentation or for supplying air or some other media into the interior of the rotary drum member 12 of the mill.

65 Within the rotatable shell or drum member 12, is dis-

70 suitable sealing or packing material may be utilized in a conventional manner in conjunction with bearings 32 and end cap member 34 for preventing the leakage of vapor through the hollow interior of trunnions 14 from the interior of the drum member. A generally axial extending secondary pipe or duct 36 may also be providing extending through duct section 28 of the vent pipe 24 and communicating with the interior of the drum member 12. Duct 36 may be for the purpose of receiving instrumentation or for supplying air or some other media into the interior of the rotary drum member 12 of the mill.

75 Within the rotatable shell or drum member 12, is dis-

posed a shield element 40 for protecting vent structure 24 against the ball charge and/or the product disposed in the drum during operation thereof. Shield 40 comprises a body portion 42 and end supporting portions 44 and 45. While a supporting portion is shown on either end of the body portion of the shield, it will be understood that the latter could be so constructed so as to be supported at only one end thereof. End portion 44 which is disposed adjacent end wall 12a of drum 12 is supported on or by fixed duct portion 28 of vent structure 24, while the other 45 of the end portions, which is disposed adjacent end wall 12b of the drum 12, may be supported on a stationary shaft or supporting member in a generally similar manner as aforescribed in connection with end portion 44. It will be seen, therefore, that shield 40 is nonrotatable with respect to the associated drum member 12. The body portion 42 of the shield commences adjacent the top of drum 12 in comparatively closely disposed relation therewith, and curves downwardly in a sharper arc than does the confronting interior surface of the drum, to thereby define a widened bottomed passageway 47 (Fig. 3) for the generally free access of vapors and/or air to the vent structure 24. The body portion of the shield 40 is provided with a lengthwise extending recessed or hollowed portion 48 (Fig. 3) for receiving in complementary supporting relation the duct section 25 of vent structure 24. As is illustrated in Fig. 3 of the drawings, the shell or drum member 12 of the mill is adapted to rotate in the direction of the full line arrow A thereby causing the ball charge and product B being handled or processed by the mill to pile up or occupy the generally right hand side (as viewed in Fig. 3) of the drum. It will be apparent that shield 40 will effectively prevent any of the ball charge or product being handled or processed from striking or entering the vent pipe 24 and yet the vapor and/or air in the interior of the mill may readily rise or pass through passageway 47 defined by the shield 40 and confronting interior surface of drum 12, and as is illustrated by the dot-dash arrows in Fig. 3, to the vent structure 24. It will also be seen that the end portion 44 of shield 40 is generally molded or bowed around vertical duct section 25 of vent structure 24, and thus protects the latter section from injury, due to the tumbling or moving ball charge and product in the mill interior. Portion 44 also prevents the charge from passing into duct 36 while still permitting atmospheric communication between the interior of the mill and duct-work 36.

The venting and shielding mechanism occupies a minimum of operating space interiorly of the mill and does not interfere in any manner with the mill's functioning. In this connection, it will be seen that the venting apparatus 25, is inclined away from the vertical longitudinal center plane of the mill in the direction of rotation thereof (Fig. 3), to thereby occupy generally non-operating space in the interior of the mill.

A mill of the above construction may be used as a chemical reactor where vapors must be removed during operations, or it may be operated under vacuum, for example to assist in the removal of occluded gases from the product, or the product being processed in the mill could be charged in the form of a slurry mixed with a solvent which could then be vaporized by suitable means such as the auxiliary heating jacket 50 encircling the exterior of the ball mill, and removed through the vent structure 24 so that the product being handled could be better ground dry, after which the solvent removed could then be reintroduced into the mill interior to reslurry the product prior to discharge thereof. As may be seen in Fig. 1, suitable piping 52 and associated rotary union connector may be provided for furnishing the heating medium to jacket 50. Another environment in which the ball mill could be advantageously utilized would be under the condition where it was desirable to evacuate the mill interior and back-fill with an inert atmosphere, prior to

the introduction of the product, to avoid a non-desirable atmospheric reaction. It will be seen, therefore, that various combinations of the above operations could be employed to obtain any desired end result. While the configuration of the ball mill illustrated has been of generally cylindrical shape, it will be understood that other designs of rotatable shell members could be utilized in conjunction with the venting and shield arrangement shown, so as to provide for continuous venting of the mill interior during operation of the mill, and without interference with the said operation thereof. The shield and vent arrangement is compatible with alloy metal as well as with ceramic lined mill constructions.

From the foregoing description and accompanying drawings, it will be seen that the invention provides a material handling mechanism of the ball mill type, which includes venting structure for continuously venting or drawing off the atmosphere interiorly of the mill during operation thereof and in combination with shield structure for protecting such venting mechanism from the charge being handled in the mill. In addition, the invention provides a mill structure which is adaptable for use in a great variety of conditions and operations where it is necessary or desirable to introduce or remove media into or from the interior of the mill, thus greatly enhancing the useability of the mill, such operations being performable during operation of the mill.

The terms and expressions which have been employed are used as terms of description and not of limitation, and there is no intention in the use of such terms and expressions of excluding any equivalents of any of the features described or shown or portions thereof, but it is recognized that various modifications are possible within the scope of the invention claimed.

I claim:

1. In a ball mill comprising a supporting frame, a shell member mounted on said frame for rotation about a generally horizontally extending axis, said shell member being adapted to receive a charge of balls and product therein to be processed, elongated venting means disposed in said shell member and extending exteriorly thereof generally along the axis of rotation of said shell member, said venting means being mounted in stationary relation with respect to said supporting frame and being disposed generally adjacent the interior surface of said shell member, said venting means comprising an elongated upper section extending generally horizontally interiorly of said shell member and a generally downwardly projecting section interiorly of said shell member and communicating with one end of said upper section, said downwardly projecting section extending generally transverse to the axis of rotation of said shell member and communicating at its lower end with another venting section extending exteriorly of said shell member along the axis of rotation thereof, and shielding means coating with said venting means to prevent the charge of balls and product from direct contact with said venting means, said shielding means being mounted in stationary relation with respect to said supporting frame and comprising a body portion of arcuate shape in vertical section extending generally parallel to and in juxtaposed relation to said upper section of said venting means, said shielding means including at least one downwardly extending end portion supporting said body portion in spaced relation to the axis of rotation of said shell member, said venting means being disposed intermediate the interior surface of said shell member and said shielding means to thereby protect said venting means from direct contact with the charge, said end portion being bowed outwardly and disposed in protecting relation about said downwardly extending section of said venting means.

2. In a ball mill in accordance with claim 1, wherein said body portion of said shielding means has a lengthwise recess disposed therein and receiving in complementary

supporting relation said upper section of said venting means.

3. In a ball mill comprising end supporting structure, a hollow drum member mounted for rotation on a generally horizontal axis extending between said end supporting structure, said drum member being adapted to receive therein a charge of product to be processed and grinding balls for accomplishing the same, the end walls of said drum member having axial and outwardly extending trunnion portions secured thereto, at least one of said trunnions being hollow and open at both ends thereof, vent means extending from the exterior of said drum member into the interior thereof, said vent means comprising a generally step-shaped duct, one section of which extends axially through said one trunnion portion and another section of which extends lengthwise in the interior of said drum member generally adjacent the inner periphery thereof and parallel to the axis of rotation of said drum member, said sections being connected by a generally vertically extending section which is angularly displaced from the longitudinal vertical center plane of said drum member in the direction of rotation thereof, means disposed intermediate said one duct section and the interior of said one trunnion portion to prevent leakage from the interior of said drum member, means for holding said vent means in stationary relation on the associated of said end supporting structure, and shielding means disposed interiorly of said drum and coaxing with said vent means to prevent engagement of the charge with said vent means during rotation of said drum, said shielding means comprising a generally lengthwise extending body portion

adapted to be disposed intermediate the charge and said vent means and at least one end portion connected to said one duct section of said venting means and supporting said shielding means in stationary relation to said end supporting structure, said body portion of said shielding means being of arcuate configuration in vertical section with the center of curvature thereof being disposed in spaced relation to the center of curvature of the interior surface of said drum member, said body portion commencing adjacent the top of the drum interior and curving downwardly and away from the confronting interior surface of said drum member to define a widened bottom passageway for the free access of vapors to said vent means.

15 4. In a ball mill in accordance with claim 3, wherein said one section of said vent means comprises an auxiliary duct disposed in telescoped relation interiorly thereof, said auxiliary duct at its inner end being in communication with the interior of said drum member and at its 20 other end projecting exteriorly of said one section.
